UNITED STATES PATENT OFFICE.

NATHANIEL C. GREENE, OF NEW YORK, N. Y., ASSIGNOR TO POLYMET MANUFACTURING CORPORATION, A CORPORATION OF NEW YORK.

ELECTRICAL PLUG.

Application filed May 18, 1926. Serial No. 110,079.

This invention relates generally to electrical plugs of the telephone type adapted for use in connection with radio receiving sets or telephones to improve the quality of the tone reproduction at the loud speaker or headphones.

The invention which is the subject matter of this application is an improvement and simplification of my companion application filed simultaneously herewith, Serial No. 110,080, filed May 19, 1926.

The improved quality of the tone reproduction is obtained by inserting a by-pass condenser across the terminals in the body portion of the plug. This condenser improves both the high and low notes of the musical register by broadly increasing the audio frequency range. The condenser also by-passes the stray radio frequency currents which pass over into the audio stages of the set and also prevents the pulsating current obtained from faulty "B" batteries from passing through the speaker unit; thereby eliminating the crackling and other foreign noises due to these stray currents which are greatly amplified by the loud speaker and cause poor reproduction.

By inserting the condenser in the body portion of the plug, I accomplish the results immediately which would otherwise require considerable changes to be made in a large percentage of the radio sets in use to-day as they are so enclosed and constructed to practically necessitate taking the set apart to insert the condenser in the hook-up; and if the set were accessible, the average layman would not know how to attach the condenser or where to place the same.

My improved phone plug also provides for the possibility of operating a plurality of loud speakers or sets of head phones. This provision is made by providing the body portion of the plug with binding posts which are in contact with the condenser connections.

One of the objects of my invention is to provide a radio phone plug which will improve the quality of the tone reproduction.

Another object of my invention is to increase the audio frequency range of a radio receiving set and thereby improve the high and low notes of the musical register.

Another object of my invention is to eliminate the stray radio frequency currents and

prevent the pulsating current from faulty "B" batteries from passing through the speaker unit.

Another object of my invention is to provide a radio phone plug with means for attaching more than one loud speaker or sets of head phones.

Another object of my invention is the provision of means to securely hold the lead wires of a speaker unit or head phone in such a way so as to prevent the same from being accidentally dislodged.

Another object of my invention is to provide a radio phone plug having a condenser located within its body portion and connected across its terminals which will improve the reproduction at the loud speaker or head phones, and which will eliminate the necessity of taking the receiving set apart or dismantling it to any extent to obtain the improved reproduction.

A further object of my invention is to provide a neat, simple and inexpensive device which will be attractive in appearance, durable and not subject to excessive strain or wear, and which entirely encloses a condenser and the necessary connections in a body of insulating material.

With these and other objects in view, to be more fully set forth hereinafter, the invention consists in the novel construction, combination of elements and arrangement of parts which will be exemplified in the operation and construction herein described in the following specification and illustrated in the accompanying drawings.

The invention will first be described in connection with the accompanying drawings, wherein similar reference characters are used to designate corresponding parts throughout the several views, and more specifically defined and indicated in the appended claims.

Attention is directed to the drawings in which:

Fig. 1 is a plan view of my improved radio plug,

Fig. 2 is a side view of the same,

Fig. 3 is a plan view of the lower half illustrating how the lead wires are inserted and held in position,

Fig. 4 is a sectional view taken on the line 4-4 of Fig. 3,

Fig. 5 is a sectional view taken on the line 5-5 of Fig. 3,

Fig. 6 is a detail view of a modified form of terminal,

Fig. 7 is a partial sectional side view illustrating a modified form of my invention,

Fig. 8 is a detail view of one of the terminals used in the modified form illustrated in Fig. 7.

Referring to the drawings, the body portion of my improved plug consists of the two halves 1 and 2, each an exact replica of the other and preferably molded from a suitable insulating material such as hard rubber, bakelite, redmanol, porcelain or any other of the common insulating materials which can be molded. The inner faces of the halves 1 and 2 have recesses or depressions 3 molded in them to form the chamber 3^a, said halves being securely held together by the countersunk screws 4. (See Fig. 1.) Leading into the depressions 3 at an angle from the edge of the halves 1 and 2 are the depressions 5 forming the diverging bores 5^a, and forming the opening 6^a and the post 7 are the depressions 6.

Located in suitable depressions in one end of the body halves 1 and 2 is the plug terminal assembly consisting of the terminals 8 and 9 which are insulated from one another by the washers 10 and 11. Securely held at one end of the terminal assembly and in electrical contact with each of the terminals 8 and 9 are the spring terminals 12 and 13; said spring terminals being insulated from each other by the washer 11. The spring terminals 12 and 13 are so positioned to oppose one another and have the condenser 14 securely fastened between them by means of the rivets 15. Integral with the terminals 12 and 13 are the extending contact portions 16 which are bent outward to form a spring contact with the contact buttons of the binding posts 17 when the halves 1 and 2 forming the body are fastened together, as is illustrated most clearly in Figs. 4 and 5. The binding posts 17 are centrally located in suitable holes molded in the halves 1 and 2 and are held in position by the threaded washers 18. The holes 19 drilled in the binding posts are provided for the reception of a second pair of lead wires from a loud speaker or head phones, said wires being held securely by screwing down on the knurled thumb nuts 20. Integral with the spring terminals 12 and 13 are the spring contacts 21 which extend into the diverging bores 5^a as illustrated in Figs. 3 and 4. The ends of the spring contacts 21 are bent backwards to make a wiping contact with the metal tips 22 on the ends of the wires 23 when they are forced home in the bores 5^a as illustrated in Fig. 3. The recesses 24 are provided to allow the ends of the spring contacts to recede when the metal tips are forced home.

To connect my radio plug with a loud speaker or head phone, the wires 23 termi-

nating in the metal tips 22 are passed through the opening 6^a formed by the depressions 6 in opposite directions to each other before inserting the tips into the bores 5^a. Any direct pull on the wires 23 is taken up by the post 7 and the tips, which are pulled sideways due to the crossing of the wires; said sidewise pull causing the tops to bind in their respective bores and thereby preventing them from being pulled out of contact accidentally.

The modified form of spring terminal illustrated in Fig. 6 differs from the one illustrated in the preferred form in that, instead of having a contact portion 16 for the binding posts extending from its end, it has the contact portion 16^a integral therewith extending from its side.

The modified form of my radio plug as illustrated in Fig. 7 differs from the preferred forms in that, the binding posts for the second set of loud speaker or head phone wires have been eliminated and the spring terminal 12 does not have integral therewith a spring contact 16 or 16^a (see Fig. 8) which is only needed when the binding posts are used.

In accordance with the provisions of the patent statutes, I have described my invention, but I desire it is understood that it is not confined to the particular form shown, and described, the same being merely illustrative, and that the invention can be carried out in other ways without departing from the spirit of my invention, and therefore, I claim broadly the right to employ all equivalent instrumentalities coming within the scope of the appended claims, and by means of which objects my invention are attained and new results accomplished; as it is obvious that the particular embodiments herein shown and described are only some of many that can be employed to attain these objects and accomplish these results.

Having now described my invention, what I claim and desire to secure by Letters Patent, is:—

1. In a device of the character described, a hollow casing, electrical terminal devices at the ends of the casing, a condenser of the square block type within the casing and a pair of sheet metal plates bridging the side walls of said casing from end to end and providing electrical connections for said terminal devices to said condenser, and mechanical support for the latter free of the walls of the casing.

2. In a device of the character described, a hollow casing, electrical terminal devices at opposite ends of the casing, a pair of electrical terminals disposed on opposite sides of the casing intermediate its ends, a condenser of the square block type positioned within the casing, and a pair of sheet metal plates extending through the casing and providing electrical connections for said termi-

nal devices and said condenser and mechanical support for said condenser free of the walls of said casing.

3. In a device of the character described, a hollow casing, a jack plug at one end of the casing, conductor wire tip receiving sockets at the other end of the casing, a pair of binding posts disposed on opposite sides of the casing intermediate its ends, a condenser of the square block type positioned within said

casing and a pair of sheet metal plates extending through the casing and providing electrical connection for said plug, receiving sockets and binding posts to the condenser and mechanical support for said condenser free of the walls of said casing.

This specification signed this 17th day of May, 1926.

NATHANIEL C. GREENE.
